(57) **CLAIM**

The ornamental design for a nail clipper as shown and described.

DESCRIPTION

FIG. 1 is a front, right, and top perspective view of a nail clipper, showing my design;
FIG. 2 is a rear, left, and bottom perspective view thereof;
FIG. 3 is a front elevation view thereof;
FIG. 4 is a rear elevation view thereof;
FIG. 5 is a left side elevation view thereof;
FIG. 6 is a right side elevation view thereof;
FIG. 7 is a top plan view thereof; and,
FIG. 8 is a bottom plan view thereof.

The broken lines depict portions of the nail clipper that form no part of the claimed design.
